(57) **CLAIM**

The ornamental design for an panel for integrated multi-function optical disk drive module, as shown and described.

DESCRIPTION

FIG. 1 is a perspective view of the design according to an embodiment of the invention.

FIG. 2 is a front view of the design according to an embodiment of the invention.

FIG. 3 is a top view of the design according to an embodiment of the invention; and,

FIG. 4 is a right side view of the design according to an embodiment of the invention.

The broken lines are shown for illustrative purposes only and form no part of the claimed design.
